UNITED STATES PATENT OFFICE

2,100,879

ELECTRIC LAMP

Richard E. Smith, East Cleveland, Ohio, assignor
to General Electric Company, a corporation of
New York

Application July 29, 1936, Serial No. 93,236

4 Claims. (Cl. 176—16)

My invention relates to electric lamps and more particularly to such lamps having a gas filling. Still more particularly, my invention relates to means for preventing the blackening of the bulbs or envelopes of such lamps.

In gas-filled electric lamps having a light source of refractory metal such as tungsten, vaporized particles of the metal are carried by the convection currents within the bulb and are deposited on the walls of the said bulb in the form of a dark coating which absorbs some of the light and thereby reduces the useful life of the lamp.

One of the objects of my invention is to provide a simple means for effectively preventing the blackening of the bulbs of gas-filled lamps. According to my invention, bulb blackening is prevented by means of a screen, preferably a metal screen, located above the light source so as to be in the path of particles vaporized therefrom, the screen being so arranged as to provide a comparatively large surface extending along the path of the convection currents in the bulb for receiving the deposit of vaporized particles without materially affecting the path of the convection currents. Other features and advantages of my invention will appear from the following detailed description of a species thereof.

In the drawing, Fig. 1 is an elevation of a high intensity gas-filled incandescent lamp comprising my invention, and Fig. 2 is a section taken along the line 2—2 of Fig. 1.

Referring to the drawing, the lamp illustrated is of the so-called "bipost" type disclosed in United States patent application Serial No. 57,196, 35 Daniel K. Wright, filed January 2, 1936. The lamp comprises a tubular glass envelope or bulb 10 having a cup-shaped glass body 11 sealed to the end or neck thereof and containing an inert gas or gases such as argon or nitrogen or a mixture thereof. A pair of metal terminal posts 12 are sealed to the glass cup 11 and each consists of a cylindrical prong 13 having a thin metallic cup or flare 13' secured thereto and sealed at its rim to the said glass cup 11. The prongs 13 extend through openings in the glass cup 11 into the bulb 10 and each has secured thereto an end of a rigid lead 14 which extends longitudinally into the bulb. A filament 15, preferably of tungsten, is mounted in the lower end of the bulb 10 and is of the monoplane type in which the coiled sections are located substantially in a single plane which preferably passes through the longitudinal axis of the bulb 10. Each of the ends of the said filament is secured to one of the leads 14 and the intermediate portions thereof are supported by

the ends of upper and lower support wires 16 and 17. The opposite ends of said support wires 16 and 17 are secured to bridges or blocks 18 and 19 respectively of insulating material extending between the leads 14 and secured thereto by pieces 5 of wire 20.

Blackening of the bulb 10 is prevented and vaporized particles from the filament 15 are collected by a pair of wire screens 21 each mounted on and preferably electrically connected to one 10 of the leads 14 and extending to a position adjacent the opposite lead. The screens may be made of nickel and are preferably spot welded to the leads by means of narrow strips of metal 22 placed over the ends thereof. Additional support is provided for the screens by wires 23 secured at one end to the bridge piece 18 and extending upwardly and welded or otherwise secured to said screen. The screens 21 are thus mounted directly above the filament 15 and closely adjacent to the plane of said filament so as to be in the path of particles vaporized therefrom. The screens extend longitudinally of the bulb 20 a substantial distance so as to provide a comparatively long surface which does not excessively 25 impede the normal circulation of the gas in the bulb and yet readily collects the vaporized particles.

The action of the screen appears to be principally a mechanical one of intercepting the vaporized particles carried along the screen by the convection currents. However, there also appears to be an advantage in electrically connecting the screens to the leads so that they are at the same potential as the leads, thereby creating 30 an electrical field between them, and also an electric field between each screen and the lamp filament, which acts on the charged particles vaporized from the filament to cause them to be deposited on the screens.

Since the vaporized particles are carried upward by the convection currents, it is necessary that the lamp be used in such a position that the screen is above the filament. The lamp shown in the drawing is, therefore, designed for 45 base-up operation. In case it is desired to operate the lamp base-down, it is necessary to interchange the positions of the filament 15 and screens 21 on the leads 14 so that the screens will be above the filament during operation of the 50 lamp. It is also possible to employ only one of the screens 21 instead of two screens.

What I claim as new and desire to secure by Letters Patent of the United States is:

1. An electric lamp comprising a bulb having 55

a gaseous atmosphere therein, a metallic light source in said bulb defining a substantially vertical plane and a flat screen located substantially in the plane of said light source and above said light source when the lamp is in use so as to extend along the path of particles vaporized from said light source.

- 5 2. An electric lamp comprising a bulb having a gaseous atmosphere therein, a pair of leads extending longitudinally of said bulb, a metallic filament located between said leads substantially in the single longitudinal and vertical plane passing through said leads and electrically connected at each end to one of said leads, and a flat screen 10 located between said leads and substantially in the said plane passing through said leads and above said filament when the lamp is in use so as to extend along the path of particles vaporized from said filament.
- 15 3. An electric lamp comprising a bulb having a gaseous atmosphere therein, a pair of leads extending longitudinally of said bulb, a metallic filament located between said leads substantially in the single longitudinal and vertical plane pass-

ing through said leads and electrically connected at each end to one of said leads, and a flat metallic screen located between said leads and substantially in the said plane passing through said leads and above said filament when the lamp is 5 in use so as to extend along the path of particles vaporized from said filament, said screen being electrically connected to one of said leads.

4. An electric lamp comprising a bulb having a gaseous filling therein, a pair of leads extending 10 longitudinally of said bulb, a metallic filament of the monoplane type located between said leads in the plane passing through said leads and electrically connected at each end to one of said leads, and a pair of flat metallic screens each mounted 15 on and electrically connected to one of said leads and extending to a position adjacent the other lead, said screens being closely adjacent to the plane passing through said leads and being located above said filament when the lamp is in 20 use so as to be in the path of particles vaporized from said filament.

RICHARD E. SMITH.
